UNITED STATES PATENT OFFICE.

ANTHONY KENNEDY, OF DREXEL HILL, PENNSYLVANIA, ASSIGNOR OF ONE-HALF TO
THE HOLLAR COMPANY, OF PHILADELPHIA, PENNSYLVANIA, A CORPORATION OF
NEW YORK.

VAULT.

Application filed November 8, 1923. Serial No. 673,483.

My invention relates to vaults of the general class of my invention described in Letters Patent of the United States 591,188 dated October 5, 1897, wherein the several 5 walls of the inclosure are formed of respective steel armor plates having interlocking means at their junctions. At that time; such plates were only obtainable in plane slabs and, consequently, at each edge of the 10 inclosure, the edge of the slabs in at least one of the walls was necessarily exposed so that at its junction with the slabs of the wall extending transversely thereto, an interstice was presented, manifesting the 15 thickness of the wall slabs and affording a region for attack at every edge of such inclosure.

In accordance with my present invention; a vault inclosure may be formed with 20 members at each edge of each wall having portions extending into walls in transverse relation with each other. In fact, in the rectangular inclosure chosen for illustration herein, I provide corner members which 25 each have three portions, in unitary relation, respectively extending into three walls of the inclosure which are in right angular relation to each other. Such construction and arrangement avoid the necessity of exposing the edges of the wall slabs of the 30 inclosure; render it impossible to ascertain from the exterior of the structure what is is the thickness of the wall slabs, and render the inclosure corners imperforate and without any interstice affording a region of attack. Moreover, the construction and 35 arrangement described facilitate the operations both of manufacturing and of assembling the inclosure slabs, and lessen the 40 time and labor heretofore required for the construction of a vault of the class specified.

Furthermore, it is characteristic of the structure shown in said Letters Patent 591,188 and also of the structure shown in 45 Letters Patent of the United States 1,053,815 relating to vaults of the same general class, that some of the wall members required to complete a rectangular inclosure must be applied from the outside. That is to say; 50 the space required in which to assemble such an inclosure is larger than the completed inclosure. The effect of that characteristic of the prior art is that the vault inclosure must be assembled before the masonry walls 55 of the building in which it is located can be

erected around it. Therefore, a highly important advantage of my present invention is that a vault may be constructed in accordance therewith within a chamber in a previously erected building, which chamber is 60 no larger than the vault structure when completed; as the walls of a vault, in accordance with my present invention, may all be assembled in the vault inclosure from the inside thereof. In other words; my 65 present invention permits of the completion of the masonry part of a building in which a vault is to be erected before the vault is erected; instead of afterward, as required by the prior art aforesaid. 70

My invention includes the various novel features of construction and arrangement hereinafter more definitely specified.

In said drawings: Fig. I is a perspective view of a vault inclosure embodying a simple form of my invention. 75

Fig. II is a longitudinal sectional view of said vault, taken on the line II, II in Fig. I.

Fig. III is a fragmentary, longitudinal, 80 sectional view similar to Fig. II, but showing a joint between a bottom wall or floor slab and a side wall slab constructed and arranged as described in my Letters Patent No. 591,188 aforesaid, and which may be 85 used in conjunction with the super-structure shown in Fig. II.

Fig. IV is a top plan view of a vault embodying a modified form of my invention, 90 which is more complex than that shown in Figs. I and II, in that it is formed of a larger number of wall members of unit sectional type.

Fig. V is a plan sectional view of the vault inclosure shown in Fig. IV, showing 95 the interior construction and arrangement of the wall members thereof.

Fig. VI is a perspective view of a modified form of corner member.

Referring to the form of my invention 100 shown in Figs. I and II; the several corners of the inclosure 1 are formed of respective single pieces 2 each having portions extending in connection with three walls of the inclosure in right angular relation to 105 each other. For instance, the corner piece 2 at the corner nearest the observer in Fig. II, has portions 3, 4 and 5 respectively in connection with the top wall 7, front wall 8 and side wall 9. I find it convenient to 110

connect said corner angle members 2 by side angle members 10 which are alike in that each includes portions 11 and 12 at right angles to each other and in unitary relation, 5 which are connected with the adjoining walls which are at right angles to each other. For instance, the top edge members 10 immediately over the door 14 in Fig. I has portions 15 and 16, at right angles to 10 each other, respectively connected with said top wall 7 and front wall 8 which are at right angles to each other.

Said corner members 2 and edge members 10 thus form a rectangular frame for the walls of said inclosure 1, and the panel openings in such frame may be filled by single slabs, for instance, like the front wall slab 8, or by a series of slabs such as indicated at 18, forming the top wall 7 in conjunction with the frame members aforesaid. As indicated in Fig. I, there are three such wall slabs 18 included in the top wall 7 and three similar slabs 19 are included in the side wall 9. However, it is to be understood that any desired number of slabs may be used to form a wall in accordance with 25 my invention.

As shown in Fig. II; I prefer to so form each of the wall members that it is adapted 30 to overlap the wall members immediately adjoining it. For instance, each of said corner members 10, in that figure, is recessed upon its inner faces at each of its edges; the outer recess 20 being of less 35 extent than the inner recess 21 and leaving a projecting flange 22 at the outer portion of the thickness of said member 10. As indicated at the upper left hand corner of Fig. II; said corner member 10 is thus 40 adapted to fit in complementary relation with the adjoining wall members. For instance, the front wall slab 8 has recesses 23 at its edges adapted to receive the projecting flanges 22 of the corner members 10 45 and said plate 8 has projecting flanges 24 fitted to the recesses 20 in said corner members. Said plate 8 also has recesses 25 respectively registering with the recesses 21 in said corner plates so as to receive the 50 coupling bars 27 which bridge the joints between said wall members and cover the crevices between them and are respectively rigidly connected therewith by screw members 28.

As indicated in Fig. II, I also find it 55 convenient to provide the overlapping wall slab flanges 22 and 24 aforesaid with complementary semicylindrical grooves to receive the locking rod 30. Although, as indicated in Fig. II; the bottom wall 31 may be formed of wall slabs 18 like the top 60 wall 7 and be connected with the side walls by the intermediate corner members 10 above described; the construction may be simplified by forming the bottom joints be-

tween the bottom wall and side walls as in Fig. III, which shows a construction and arrangement disclosed in my Letters Patent No. 591,188 aforesaid. In Fig. III, the bottom wall slab 32 has an undercut channel 33 at the edge thereof adapted to receive a complementary flange 34 on the side wall slab 35 and said slabs are held in interlocked position by the wedge strip 36.

Referring to the form of my invention 75 shown in Figs. IV and V; the several top corners of the inclosure 41 are formed of respective angle pieces 42 each having portions extending in connection with three walls of the inclosure in right angular relation to each other. For instance, the corner piece 42 at the upper left hand corner of Fig. IV, has portions 43, 44 and 45 respectively in connection with the top wall 47, end wall 48 and side wall 49. I find it 80 convenient to connect said corner angle members 42 by side corner angle members 50 which are alike in that each includes portions 51 and 52 at right angles to each other and in unitary relation, and which 85 are respectively connected with the adjoining walls which are at right angles to each other. For instance, the top corner edge member 50 shown at the upper edge of Fig. IV has portions 51 and 52 at right angles to each other respectively connected with 90 said top wall 47 and front wall 48 which are at right angles to each other.

Said corner members 42, which have 95 three portions extending in planes in transverse relation to each other, and said corner members 50 which have two portions extending in planes in transverse relation to each other, form a rectangular frame 100 for the walls of said inclosure 41, and the panel openings in such frame may be filled by single slabs or by a series of slabs. For instance, as indicated in Fig. IV; there are three such wall slabs 58 forming said top 105 wall 47 in conjunction with the corner frame members 42 and 50 aforesaid. However, as indicated in dotted lines in Fig. IV and shown in full lines in Fig. V, each of the opposite end walls of said inclosure 41 110 includes two wall slabs respectively 59 and 60, which, incidentally, differ in the construction and arrangement of the rectangular recesses 61 and flanges 62 at the opposite edges thereof; said wall slabs 59 having 115 projecting flanges which are offset inwardly from the outer surfaces thereof and said wall slabs 60 having one such flange offset inwardly and the other flush with the outer surface of the slab and of the inclosure. Similarly, as indicated in Fig. V, the corner members 50 may have such overlapping flanges 63 and complementary recesses 64 either flush with their outer surfaces and with the outer surfaces of said 120 inclosure 41, or offset inwardly therefrom,

whichever is most convenient to facilitate the assembling of such vault members with the adjoining corner pieces or slabs. However, said flanges on all of the wall members above described are so constructed and arranged as to overlap complementary flanges and extend in complementary recesses in the adjoining wall members.

However, each of said wall members 42, 50, 58 etc., has, in addition to the flange recesses above described, rectangular coupling bar recesses 66 at the edges of its inner surface to receive rectangular coupling bars 67 so that said coupling bars bridge the joints between the adjoining wall members and the inner surfaces of said bars are flush with the inner surfaces of said inclosure 41 when set in said coupling bar recesses and, as indicated in Fig. V, said coupling bars may be rigidly connected with the adjoining wall members by screw members 69 which are inserted from within said vault inclosure and are flush with the inner surface thereof.

As indicated in Fig. V; the lower wall 71 of said inclosure 41 may be formed of outer corner members 42 and 50 and panel slabs 72 similar to the slabs 58 in the top wall 47, having complementary overlapping flanges and recesses and coupling bars bridging the joints between such wall members, as above described.

As above noted; the flanges on the respective wall members adapted to overlap and interengage the adjoining wall members may be either at the outer surface of the inclosure or offset inwardly with respect thereto, as may be most convenient in assembling the various parts of the structure. However, in Fig. VI, I have shown a corner member 74 having portions 75, 76, and 77 respectively extending in planes which are in transverse and right angular relation to each other, adapted to register with wall slabs of the character above described, but some of said transversely related portions have flanges 79 at the outer surfaces thereof and others have flanges 80 offset inwardly with respect to such outer surfaces. In order to facilitate the construction of a wall member of that character; I find it convenient to form it of what are primarily two separate pieces of metal which are, however, integrated by screw members 81 or by any other convenient means, for instance, the component elements of such wall members may be spot welded together.

Therefore, it is to be understood that although the construction and arrangement aforesaid are designed and adapted for employment of massive unitary wall members of steel armor plate; they may be formed of other metal and may be composed of more than one piece, providing that if formed of a plurality of primarily separate pieces, such pieces are integrated by suitable means

rigidly connecting them to form a structural unit wall member having the characteristics above described. For instance, suitable integral and massive wall members embodying my invention herein claimed may be composed of cast steel structural units having, imbedded therein, protective plates of more refractory material, as described and claimed in my copending application Serial No. 673,482 filed November 8, 1923 for Letters Patent of the United States.

Therefore, I do not desire to limit myself to the precise details of construction and arrangement herein set forth, as it is obvious that various modifications may be made therein without departing from the essential features of my invention, as defined in the appended claims.

I claim:

1. In a safety vault inclosure, the combination with integral and massive plane, slab wall members of steel armor plate; of integral and massive angular corner wall members of steel armor plate, having three portions extending in respective planes at right angles to each other and arranged to respectively engage said slabs; said slabs and corner members having complementary rectangular edge flanges and flange recesses; said flanges of adjoining members arranged to overlap and extend in the respective flange recesses; said slabs and corner members having complementary rectangular coupling bar recesses; rectangular plane coupling bars arranged to fit in said bar recesses and overlap the joints between said members; said bars being then flush with the inner surfaces of the respective walls of said inclosure; and screw means rigidly securing said bars to said wall members; said screw means being flush with the inner surfaces of the respective inclosure walls.

2. In a safety vault inclosure, the combination with integral and massive plane slab wall members of steel armor plate; of integral and massive angular corner wall members of steel armor plate, having portions extending in respective planes at right angles to each other and arranged to respectively engage said slabs; said slabs and corner members having complementary rectangular edge flanges and flange recesses; said flanges of adjoining members arranged to overlap and extend in the respective flange recesses; said slabs and corner members having complementary rectangular coupling bar recesses; rectangular plane coupling bars arranged to fit in said bar recesses and overlap the joints between said members; said bars being then flush with the inner surfaces of the respective walls of said inclosure; and screw means rigidly securing said bars to said wall members; said screw means being flush with the inner surfaces of the respective inclosure walls.

3. In a safety vault inclosure, the combination with integral and massive plane slab wall members of metal; of integral and massive angular corner wall members of metal, having portions extending in respective planes at right angles to each other and arranged to respectively engage said slabs; said slabs and corner members having complementary rectangular edge flanges and flange recesses; said flanges of adjoining members arranged to overlap and extend in the respective flange recesses; said slabs and corner members having complementary rectangular coupling bar recesses; rectangular plane coupling bars arranged to fit in said bar recesses and overlap the joints between said members; said bars being then flush with the inner surfaces of the respective walls of said inclosure; and screw means rigidly securing said bars to said wall members. 65
- 10 4. In a safety vault inclosure, the combination with integral and massive plane slab wall members of metal; of integral and massive angular corner wall members of metal, having portions extending in respective planes at right angles to each other and arranged to respectively engage said slabs; said slabs and corner members having complementary edge flanges and flange recesses; said flanges of adjoining members arranged to overlap and extend in the respective flange recesses; said slabs and corner members having complementary coupling bar recesses; coupling bars arranged to fit in said bar recesses and overlap the joints between said members; and screw means rigidly securing said bars to said wall members. 70
- 15 5. In a safety vault inclosure, the combination with integral and massive plane slab wall members of metal; of integral and massive angular corner wall members of metal, having portions extending in respective planes in transverse relation to each other and arranged to respectively engage said slabs; said slabs and corner members having complementary edges arranged to interengage; coupling bars arranged to overlap the joints between said members; and screw means rigidly securing said bars to said wall members. 75
- 20 6. In a safety vault inclosure, the combination with integral and massive plane slab wall members of metal; of integral and massive angular corner wall members of metal, having portions extending in respective planes in transverse relation to each other and arranged to respectively engage said slabs; said slabs and corner members having complementary edges arranged to interengage; coupling bars arranged to overlap the joints between said members; and screw means rigidly securing said bars to said wall members. 80
- 25 7. In a safety vault inclosure, the combination with integral and massive plane slab wall members of steel armor plate; of integral and massive angular corner wall members of steel armor plate, having portions extending in respective planes at right angles to each other and arranged to respectively engage said slabs; said slabs and corner members having complementary edges arranged to interengage; coupling bars arranged to overlap the joints between said members; and screw means rigidly securing said bars to said wall members. 85
- 30 8. In a safety vault inclosure, the combination with integral and massive plane slab wall members of metal; of integral and massive angular corner wall members of metal, having portions extending in respective planes in transverse relation to each other and arranged to respectively engage said slabs; said slabs and corner members having complementary edges arranged to interengage; coupling bars arranged to overlap the joints between said members; and screw means rigidly securing said bars to said wall members. 90
- 35 9. In a safety vault inclosure, the combination with integral and massive plane slab wall members of steel armor plate; of integral and massive angular corner wall members of steel armor plate, having portions extending in respective planes at right angles to each other and arranged to respectively engage said slabs; coupling bars arranged to overlap the joints between said members; and means rigidly securing said bars to said wall members. 95
- 40 10. In a safety vault inclosure, the combination with integral and massive slab wall members of steel armor plate; of integral and massive corner wall members of steel armor plate, having portions extending in transverse relation to each other and arranged to register with said slabs; coupling members arranged to bridge the joints between said members; and means rigidly connecting said wall members and coupling members. 100
- 45 11. In a safety vault inclosure, the combination with integral and massive plane slab wall members of steel armor plate; of integral and massive angular corner wall members of steel armor plate, having portions extending in transverse relation to each other and arranged to respectively engage said slabs; said slabs and corner members having complementary edge flanges and flange recesses; said flanges of adjoining members arranged to overlap and extend in the respective flange recesses; said slabs and corner members having complementary coupling bar recesses; coupling bars arranged to fit in said bar recesses and overlap the joints between said members; and means securing said bars to said wall members. 105
- 50 12. In a safety vault inclosure, the combination with integral and massive plane slab wall members of steel armor plate; of integral and massive angular corner wall members of steel armor plate, having three
